Primary Examiner — S. Bryan Reinholdt, Jr.(74) *Attorney, Agent, or Firm* — Trojan Law Offices(57) **CLAIM**

The ornamental design for a pitcher as shown and described.

DESCRIPTION

FIG. 1 is a top perspective view of a pitcher in accordance with the present invention;

FIG. 2 is a bottom perspective view of the pitcher;

FIG. 3 is a front elevation view of the pitcher;

FIG. 4 is a rear elevation view of the pitcher;

FIG. 5 is a right side elevation view of the pitcher, the left side elevation view being a mirror image thereof;

FIG. 6 is a top plan view of the pitcher; and,

FIG. 7 is a bottom plan view of the pitcher.

1 Claim, 4 Drawing Sheets# US D1,107,485 S
